United States Patent Office

Des. 221,087
Patented July 6, 1971

221,087

BOOK BOX FOR STUDENT DESK

Roy E. Jennings, Temple, Tex., assignor to Royal
Seating Corporation, Cameron, Tex.

Filed Sept. 24, 1969, Ser. No. 19,270

Term of patent 14 years

Int. Cl. D6—01

U.S. Cl. D33—11

FIG. 1

FIG. 2

FIG. 3

FIG. 4

FIG. 5

FIG. 6

FIG. 7

FIG. 1 is a view in perspective of a book box embodying new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a vertical sectional view thereof taken along line 7—7 of FIG. 2.

The back of the book box is conventionally flat and unornamented.

I claim:

The ornamental design for a book box for student desk, as shown and described.
